SCISSORS

Francis A. Snell, Binghamton, N. Y., assignor to
Change-A-Blade Corporation, New York, N. Y.,
a corporation of New York

Application August 2, 1944, Serial No. 547,652

7 Claims. (Cl. 30—349)

This invention relates to scissors having removable blades, and to means by which the blades may be readily and securely fitted on the blade-retaining elements of the scissors.

An example of scissors of the type to which the invention relates will be found in U. S. patent to Zeidler, No. 2,177,414, and to M. L. Cohn, No. 2,355,364.

In both of these patents is shown a scissors having handle parts provided with extending shank portions on which the blades fit, and with interengaging elements by which each blade is fitted and held on its shank. In the structures disclosed in these patents, as well as in other patents in the art, the detachable blades are held in place by various means, such means usually including the pivot-screw of the scissors. This not only requires the use of a tool for removing and replacing the blades, but the removal and replacement of the pivot screw often alters the extent of frictional contact between the cutting edge parts of the blades, so that the adjustment is changed, and wholly satisfactory cutting action is not attained from the scissors.

An object, therefore, of the present invention is to provide a scissors in which the detachable blades may be removed and replaced without disturbance or removal of the pivot screw. It further contemplates the provision of means by which the blades may be removed and replaced without the use of tools, and by which a secure and accurate fitment of the blades on the shanks of the handles is attained.

A further object of the invention is to provide a blade-retaining means of a construction enabling the blade to be removed by a simple lengthwise manual pull on the blade, so that the removal and replacement of a blade can be instantly done.

In the accompanying drawing, wherein an illustrative embodiment of the invention is disclosed.

Fig. 1 is a face view of a pair of scissors in open position, embodying the invention;

Fig. 2 is a view of the inner face of one of the removable blades;

Fig. 3 is an enlarged side view of one of the handle shanks;

Fig. 4 is an enlarged view of a part of the inner face of one of the blades, showing the "button-hole" opening;

Fig. 5 is a view of the inner face of one of the handles; and

Fig. 6 is a sectional view on the line 6—6 of Fig. 2.

With reference to the structure shown, 1 and 2,

respectively, indicate the conventionally shaped handle portions. Integrally extending from each of the handles is a shank portion 3 of reduced thickness and of tapering blade-like form, and provided with the pivot-screw hole 9 for reception of the usual pivot screw 10. Near the screw hole 9 is a shoulder 7, and extending therefrom, in a direction toward the tip 6 of the shank, is an integrally-formed projection or lug 8. Near the tip 6 of the shank is a rounded protuberance or knob 5 of hemispherical shape, and located between the knob 5 and the lug 8 is a stud 4 having a shank part 4b and enlarged flat head 4a. The projecting elements 4, 5 and 8 are all located on the inside face of the shank 3, and are intended for engagement with apertures provided in the blade 11, as will be described.

The detachable blade 11 is preferably, but not necessarily, made from sheet metal, and the longitudinal edge, indicated at 11a, is the cutting edge, and the opposite longitudinal edge is stiffened or reinforced by means of a turned-down flange 12. The blade is slightly transversely concaved, as seen in Fig. 6, and is of tapering form.

Near its pointed extremity or tip, the blade is formed with a pair of slightly spaced apertures or holes 13 and 14, which are adapted to successively engage the knob 5 while the blade is being placed in position on the shank 3, and after it is positioned thereon, as will be described. Properly spaced from the holes 13, 14 is a so-called "button-hole" aperture 15, sometimes called a "key-hole" slot, adapted for engagement with the headed stud 4. At the base or butt end of the blade is formed a slot 19 of a shape to enable it to closely fit around the lug 8 on the shank 3.

In placing one of the blades on the handle part or shank 3, the enlarged portion 16 of the button-hole opening 15 is placed over the head 4a of the stud 4. At this time, the knob 5 will be resting in the hole 14. The blade is then pushed longitudinally toward the handle part 1 or 2, so that the shank 4b of the stud 4 moves up into the narrowed part 17 of the button-hole opening.

The portion of the opening 15 around the narrowed part 17 is counter-sunk, thus providing a ledge 18 which engages behind the head 4a when the blade is moved home, as described. When the head 4a is in the position just mentioned, its face will be flush with the face of the blade. This longitudinal movement of the blade causes knob 5 to snap from the inner hole 14 to the outer hole 13, and engage therein, where it serves to lock the blade against endwise movement until it is intentionally moved by pulling it in a direction toward

the tip. The rounded nature of the knob 5 enables it to move from the hole 14 to the hole 13 with a snap action. When the blade has been moved inwardly, as described, the slot 19 will be caused to engage the lug 8.

Thus, when the blade has been fitted into position, it will be found to be restrained against longitudinal movement by the engagement of the knob 5 with the hole 13; the blade is held closely against the inside face of the shank 3 by the engagement of the head of the stud 4 with the countersunk portion of the aperture 15, and will be held against the force of the cutting action by the stud 4 and the retaining lug 8.

While the elements described securely affix the blade in place, the arrangement of these parts is such that the blade may be placed on, and removed from, the handle part instantly and wholly without the use of tools, since the blade is detached by merely manually moving it in a direction toward its tip. Thus, in the embodiment described, the removal of the pivot screw 10 is unnecessary, and the removal and replacement of a pair of blades is the work of an instant.

While I have described the blade as being provided with means for holding it in place without requiring the employment of the pivot screw for that purpose, it is possible to also utilize the pivot screw for aid in holding the blade in place, when such an arrangement is deemed desirable. This, and other modifications, may be readily made without departing from the spirit of the invention.

What I claim is:

1. In a scissors of the character described, a handle having a shank portion, said shank portion being provided with a headed stud, a blade having an aperture of button-hole form for receiving the stud, said aperture including a counter-sunk part for engagement behind the head of the stud when the blade is longitudinally moved to bring the stud toward one end of the aperture, and cooperating means on the shank and blade for holding the blade against inadvertent longitudinal movement in respect to the shank, said means being located between the button-hole aperture and the tip of the blade.

2. In a scissors of the character described, a handle having a shank portion, said shank portion being provided with a headed stud, a blade having an aperture of button-hole form for receiving the stud, said aperture including a counter-sunk part for engagement behind the head of the stud when the blade is longitudinally moved to bring the stud toward one end of the aperture, and cooperating means on the shank and blade for holding the blade against inadvertent longitudinal movement in respect to the shank, said means comprising a rounded projection on the shank and an opening in the blade engaged by said projection.

3. In a scissors of the character described, a

handle having a shank portion, said shank portion having a stud projecting from its inner face, the stud having an enlarged head, a blade having an elongated aperture of button-hole form, said aperture having a part of a size permitting passage of the head, and a narrowed part through which the head cannot pass, and interengaging elements on the blade and shank for interengagement to hold the blade against longitudinal movement when the stud is located in the narrowed part of the aperture, said interengaging elements being located between the tip of the blade and the button-hole aperture.

4. In a scissors of the character described, a handle having a blade-like shank portion provided with a rib-like lugs, a projecting headed stud and a rounded projection near its extremity, all of said elements projecting from the inner face of the shank, a detachable blade having an open-ended slot in its butt end for fitment over the lug on the shank, the blade having a button-hole aperture for fitment about the stud on the shank, and the blade also having a plurality of spaced holes near its tip for successive engagement with the rounded projection when the blade is being placed on the shank.

5. In a scissors of the character described, a handle having a shank, a blade for fitment thereon, the shank having a stud projecting from its inner face, a rounded knob also projecting from the inner face of the shank, the blade having a slot-like opening for engagement with the stud, the opening being contracted in part to prevent passage of the stud therethrough when the stud is positioned in that part of the slot-like opening, and the blade also having at least two holes, one of which engages the knob when the stud is in position to pass through the opening, and the other of which engages the knob when the stud is in the narrowed part of the opening and cannot pass therethrough.

6. A scissors as called for in claim 5, wherein the slot-like opening is of button-hole or keyhole shape; wherein the blade has an open-end slot at its butt end; and wherein the shank has a lug around which the open-end slot fits when the respective interengaging elements of the blade and shank are in cooperative relation.

7. In a scissors of the character described, a handle shank and a blade for attachment to one face of the shank, means for attaching said blade, said means including a button-hole opening in the blade and a headed stud on the shank entering the button-hole opening, means for restraining the stud from movement out of the opening including a rounded projection near one end of the shank and a hole in the blade near the tip of the blade for engagement with the rounded projection when the headed stud is in engagement with the button-hole opening.

FRANCIS A. SNELL.
